William Duff and Thomas Murphy
Follows Patents

The subscriber is forced to withdraw the Follows Patent and making first of
the same a continuing description in the words of the late William
Duff and Thomas Murphy themselves of their Improvement in
the manner of raising and depressing the upper parts of steam engines.

To all to whom these presents shall come. Be it known that we William
Duff and Thomas Murphy of Baltimore in the County of Baltimore and
State of Maryland have invented a new and useful improvement in
the manner of raising or depressing the piston, or the steam & cylindering
valves in steam engines and that the following is a full and exact de-
scription of the construction and mode of operation thereof, in manner
improved by us. The object of this improvement is to place the side pipes
by which the valves of the top & bottom shafts are raised or sunk in a more lat-
ter form of construction by which we are enabled to arrange them between
the side pipes & directly beneath the top & above the lower valve so as to be
able to lift or depress the upper & lower shafts by means of a suspension chain or
pivot line between them & through these valves instead of the present plan
of placing them on the outside of the side pipes to operate on the valves by means
of levers from the side thereof projecting horizontally, as by hand gear, one set
of levers being necessary to each shaft, as the stems of the valves are not connect-
ed, & both set of stems & levers &c. are placed in the same position, or rising & down-
ing shafts which arrangement requires great inconvenience from the
springing and tremulous motion attending the great length of these shafts
& the necessary precautions to be taken against them. Our improvement con-
sists in the following arrangement of these shafts and stems so as to remedy
these defects and preserve the advantages we contemplate. The position
of the valves and shaft being the same as aforesaid, we cause at the top steam
valve the bottom cylindering valve by means of a long straight stem
reaching from one to the other of which we cast the small stem as it is to work
within

within another hollow one called a female stone and that portion of it which is to work through the stuffing box on the female stone, placed between the top & bottom shafts we call the valve stone and is made conical. The main valve which connects these two parts may be either round or square and it is to be so as to give strength from the centre to avoid springing as at the end, and is to have at each end a socket to admit the stem to be lowered into by a key, through one will have in addition a female square into which the rod will enter so that it may be lengthened or shortened at pleasure. About the centre of this rod are two lugs on each side presenting the appearance of a square mortise with shoulders for the purpose of receiving the picked left end from one of the rock shafts which is to be placed on one side of the side pipes directly opposite by the working of which with the left end the up & down motion is given to the rod and stem of the valve. The top & bottom stuffing valves & the bottom stone valve are connected by means of two shafts, placed outside of the rod & stone just described, through still between the side pipes & fastened on to the stuffing box of the male valve stone by means of long iron keys, these keys are secured on to the female stones as usual so that to work through boxes on the bottom of the top shaft & of the bottom shaft. These shafts are provided with two lugs on the outside of each as is next to the side pipes so as to produce the connection of shoulders as are formed on the rod & stones already described as situated between the two shafts. They are taken hold of by a picked right from another working shaft, placed on the opposite side of the side pipes to the one already described, so that by its working these shafts are caused to revolve in like manner as the rod and stem, though in different directions or alternately, which is provided for by connecting the arms on the working shaft by means of rods, they being both placed at the same end for that purpose and are thus made to work at the same time. The last situation for the counter is given to communicate the motion to the shafts will be on the stem of one of them. The same for side pipes we are to place to one which the valves on each stone & shafts are separated and made to work one by the side of the other instead of one with in the other. What we claim is one invention & not with a former Patent for is said the arrangement of the valve stone in the top shaft, in an inverted position so as to be connected by means of the rod with the stem of the valve in

in the lower chest, in a direct line. Secondly. The connection by means of
the stay is about set forth of the stuffing box of the forward stave of the top chest
whose box is also circular so as to be thus connected in a straight line with
the stuffing box of the lower chest and finally the adaptation of the line
connected rodding shaft as above described to produce by means of the lift-
engages the alternate motion of the string strainer.
